UNITED STATES PATENT OFFICE.

ELBERT J. HAYNES, OF CLEVELAND, OHIO.

SOUNDING LINE.

Application filed January 18, 1926. Serial No. 82,161.

This invention relates to flexible armored cables, and particularly to flexible armored air tubes for use as sounding lines and the like.

5 It is an object of the invention to provide a flexible cable having a sectional tubular outer armor, and to provide, at suitable spaced points in the length of the cable, for transmitting to a continuous tension member stresses due to the weight of the armor or to any other force longitudinally acting on the armor.

Another object is to provide a sectional outer armor for a flexible cable having certain of its sections rigidly secured to a tension member extending within the armor, so as to distribute the transmission of stresses to said tension member and avoid the undue accumulation of such stresses.

20 A further object is to provide an outer armor for flexible cables, comprising tubular sections and coiled springs, or like cushioning elements, serving to space suitable lengths of said armor, and to cushion stresses arising in such lengths due to the weight thereof, or to other forces.

A still further object is to provide an outer sectional armor for flexible cables comprising abutments fixed upon the cable at suitable points of its length for receiving longitudinal stresses arising in the armor between such points, and to cushion such stresses by coiled springs or the like, providing also for a certain longitudinally expansive movement of the free sections between said abutments.

These and various other objects the invention attains by the construction herein-after described and illustrated in the accompanying drawing, wherein:

Figure 1 is a view in elevation of a length of the improved armored cable.

Figure 2 is an enlarged view in elevation of a portion of said cable.

45 Figure 3 is a view similar to Figure 2 with portions of the outer armor members broken away to show the interior construction of the cable.

Figure 4 is a section taken on line 4-4 of 50 Figure 2 showing in detail the provision for rigidly fastening certain sections of the outer armor to the cable.

In these views the reference character 1 55 designates an air hose formed of rubber or other material having a suitable flexibility and imperviousness to air. Said hose is em-

braced by an inner armor which consists of metallic collars 2 alternating with coils 3 of spring wire, preferably of a gradual pitch.

Upon this inner armor there is helically wound a tension member 4 which may be formed of wire rope, the strands of which are acutely pitched so as to effectively take care of tension stresses acting lengthwise of the cable.

Finally there is applied an outer sectional tubular armor, preferably metallic, the sections of which have corresponding ends slightly tapered, their other ends being flat, so that the obtuse points 6 of said tapered ends bear against the flat ends of the next adjacent sections and provide for a limited pivotal movement of the sections about axes transverse to the cable established by said points. The sections 5 loosely engage the tensioning member 4 and are free to transmit their weight or other stresses to each other, and further may shift rotatively relative to said tensioning member, so as to rotatively vary the axes established by the points 6. It is undesirable to allow stresses in the sectional armor to accumulate throughout the entire extended length of the cable since the final stress transmitted to the abutment forming member at the free end of the cable may be unduly heavy, particularly when the position of the cable is such as to transmit weight downwardly from section to section of the outer armor. The present invention, therefore, provides at suitable points in the length of the cable for transmission of accumulated longitudinal stresses from the outer armor to the tension member 4. Preferably this is accomplished by securing certain of the sections 5 rigidly to the member 4. Thus, as is best seen in Figures 2 and 4, certain of said sections are

30 interiorly chambered as indicated at 7, surrounding the stranded member 4. Each of the sections, thus chambered, is formed with a pair of radial openings 8 communicating with the respective ends of the chamber 7. After the chambered sections are in proper place upon the cable, melted Babbitt metal or the like is poured through one of the openings 8 into the chamber 7 while air escapes through the other of said openings.

35 The Babbitt metal thus fills said chamber, and upon hardening anchors the section very firmly to the member 4.

40 It is desirable to provide for a limited ex-

5 pansion of each series of free sections 5 occurring between any two of the fixed sections, and to also cushion the stresses acting from the free sections upon any fixed section. For this purpose there is mounted above each fixed section 5 a coiled spring 9, sufficiently heavy to carry the weight of the overlying series of free sections without undergoing more than a slight compression.

10 10 In the use of the described cable, the fixed sections 5 act to transmit the weight of the free sections (or to transmit any other force acting lengthwise upon said free sections) to the tension member 4 of the cable, preventing the accumulation of stresses throughout the entire extended length of the cable. The coiled springs 9 cushion such shocks as are thus transmitted, and further permit a certain amount of expansion in the series of 15 free sections extending between any two fixed sections of the armor.

15 When the described construction is employed as a sounding line a portion of the cable is frequently required to drag along 20 the bottom of any body of water, in which soundings are being made, and since obstacles encountered on such bottom will at times impart sudden heavy stresses to portions of the outer armor it will be seen that 25 30 the cushioning springs 9 perform an important function.

30 It is an advantage of the described fixed abutments, arranged at spaced points in the length of the cable, that this prohibits escape 35 of all of the outer armor sections from the body of the cable in the event that the terminal abutment for said section is in any manner torn from the cable proper or in case the cable is broken.

40 40 Furthermore, when the cable is employed as a sounding line it is required to wind upon a drum such as is indicated at 10 and in engaging said drum the sectional armor is subjected to a slight tendency to longitudinal 45 expansion, which the coiled springs 9 permit.

What I claim is:

1. A cable comprising a hose, an elongated 50 flexible tension member substantially covering said hose, a tubular armor embracing said tension member comprising groups of sections seating lengthwise of the cable upon each other, and abutments fixed upon said tension member beneath said groups, each abutment receiving the accumulated thrust 55 of the armor sections of the overlying group and transmitting such thrust to said tension member.

2. A cable comprising a hose, an elongated 60 tension member substantially covering said hose, and a tubular armor embracing said

tension member and comprising certain sections fixed upon said tension member at points suitably spaced lengthwise of said member, and a plurality of groups of intermediate sections freely embracing said tension member and the sections of each group transmitting their accumulated thrust to one of said fixed sections. 65

3. A cable comprising a hose, an elongated 70 flexible tension member substantially covering said hose, and a tubular sectional armor freely embracing said tension member, and cushioning elements disposed between certain sections of said armor, and freely abutting 75 said sections.

4. A cable comprising a hose, an elongated 80 flexible tension member substantially covering said hose, a tubular sectional armor freely embracing said tension member, and coiled springs interposed between certain sections of said armor, and freely abutting 85 said sections.

5. A cable comprising an elongated flexible tension member, abutments fixed upon 90 said tension member at spaced points of its length, a series of tubular armor sections freely embracing said tension member between said abutments, and a cushioning member arranged between one of said abutments and said series of armor sections. 95

6. A cable comprising an elongated flexible tension member, abutments fixed upon 100 said tension member at suitably spaced points of its length, a series of tubular armor sections embracing said tension member between said fixed abutments, and a spring coiled upon said tension member between one of said abutments and said armor sections. 105

7. A cable comprising an elongated flexible tension member, a tubular abutment forming armor section embracing said tension member, means for securing said section throughout substantially its entire interior area to the tension member, and a 110 series of armor sections freely mounted upon the tension member and subjecting said abutment section to their end thrust.

8. A cable comprising an elongated flexible stranded tension member, a plurality of 115 tubular armor sections mounted upon said tension member, one of said sections having an interior chamber surrounding the tension member and a hardened filling within said chamber rigidly uniting the chambered section to the tension member.

In testimony whereof I sign this specification.

ELBERT J. HAYNES.
